UNITED STATES PATENT OFFICE.

GIOVANNI DE PAOLIS, OF CHRISTIANIA, NORWAY.

MEANS FOR MOLDING WALLS AND CEILINGS.

No. 826,057.

Specification of Letters Patent.

Patented July 17, 1906.

Application filed July 10, 1905. Serial No. 269,066.

To all whom it may concern.:

Be it known that I, GIOVANNI DE PAOLIS, a subject of the King of Sweden and Norway, residing at Christiania, Norway, have invented certain new and useful Improvements in Means for Molding Walls and Ceilings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to means for molding walls and ceilings.

In the annexed drawings, Figure 1 is a perspective view of a portion of a partition-wall under erection. Fig. 2 is a view of one of the 20 mold-plates, showing a preferred form of the same. Fig. 3 is an end view of one of the plates. Fig. 4 is a vertical section through the corner of a ceiling, showing the way of applying the invention for making ceilings.

25 My invention relates to that kind of walls or partitions which are formed of a quickly-hardening material, such as a composition of gypsum. To form a cheap mold for making such partitions, (be it walls or ceilings,) I

30 make use of plates *g*, the form of which is shown in Figs. 2 and 3. As will be seen, the mold-plates all around have projecting flanges *g'*; but on two adjacent sides these flanges are placed on the front and on the

35 two other sides on the back face of the plate. The plates may be made of any suitable material. If they are made of wood, it is advisable to make them up of two layers of wood crossing each other, as shown in Fig. 2. When

40 using these mold-plates for forming a partition-wall, I nail two strips *a* of wood or other material on the side wall *a*, and similar strips *c* are laid down on the floor and held in the right distance from each other by means of blocks

45 *d*, nailed on the floor, and of clamps *e*, which may be secured by screws. Both the strips *a* and the strips *c* are on the inner edges provided with a notch *a'*, corresponding in size to the flanges of the mold-plates *g*. The lat-

50 ter are placed in the manner shown. I first put up one row of mold-plates in this manner, and the stuff is run in between the plates. Thereupon a second row of mold-plates are added and stuff filled in between these plates.

To hold the plates in correct distance from each other all over, distance-pieces *f* may be made use of, or small bolts, as indicated at *h*, may be inserted at the corners. I prefer to make use of a gypsum composition containing some glue solution and hardening in 55 about fifteen minutes. When the stuff has been filled in between the third row of plates, the stuff in the first row will be hardened so far that these mold-plates may now be taken away to be used for forming the fourth row. 60 The removing of the plates may be done very easily by taking off the floor-lists *c*. The other rows of mold-plates will not be liable to get loose, because they will stick to the stuff as long as it is wet and not quite hardened. 65 Walls formed in this manner may of course be strengthened by means of iron rods and the like placed between the mold-plates. When forming a ceiling in this manner, mold- 70 plates need only be used on the lower side, 75 as illustrated in Fig. 4. Also in this case strips of wood are secured to the walls to form guides for the mold-plates. Two or three rows of mold-plates may first be built up underneath the beam, and when the stuff 80 poured on has stiffened sufficiently these plates may be shifted to form new rows.

I claim—

1. Means for molding walls, ceilings and the like, comprising a plurality of rectangular mold-plates, each having a flange formed on one end and side of one face, and a corresponding flange formed on the other end and side of the opposite face, in combination with vertical retaining members each having a 85 longitudinal notch to receive one of the flanges on one face of the plate, a horizontal retaining member having a longitudinal notch 90 to receive the other flange on the same face of the plate, said retaining members and plates 95 mounted in parallel, and a plurality of like plates having their flanges of opposite faces interlocked.

2. Means for molding walls, ceilings and the like, comprising a plurality of rectangular mold-plates, each having a flange formed on one end and side of one face, and a corresponding flange formed on the other end and side of the opposite face, in combination with vertical retaining members each having a 100 longitudinal notch to receive one of the flanges on one face of the plate, a horizontal retaining member having a longitudinal notch 105 to receive the other flange on the same face of the plate, said retaining members and plates

to receive the other flange on the same face of the plate, said retaining members and plates being mounted in parallel, a plurality of like plates having their flanges of opposite faces interlocked, and distance - pieces for holding the plates parallel.

5 In testimony that I claim the foregoing as

my invention I have signed my name in presence of two subscribing witnesses.

GIOVANNI DE PAOLIS.
